UNITED STATES PATENT OFFICE.

ELMER J. MANNING, OF JANEVILLE, WISCONSIN.

CARBURETOR.

Application filed January 16, 1922. Serial No. 529,403.

This invention relates to improvements in carburetors.

It is an object of this invention to provide a novel carburetor structure in which the 5 throttle valve will be placed at the inlet to the mixing chamber and will co-operate with a special atomizing device to promote the complete atomization of the fuel.

It is a further object of this invention to 10 provide means distinct from the atomizing mechanism for apportioning correctly, the amount of fuel to be mixed with air admitted to the mixing chamber for the production of a suitable combustible mixture. 15 More specifically it is an object of this invention to control the apportionment of fuel by means of a special chamber for the regulation of depression, said chamber being interposed between the mixing chamber and 20 the source of fuel supply, and in communication with the inlet of the carburetor exterior to the throttle valve.

It is a further object of this invention to 25 provide novel and effective means for securing the atomization of all fuel delivered to the carburetor from the source of fuel supply, regardless of variations in engine performance during the period of fuel admission, provision being made also for reatomization 30 of fuel condensed upon the walls of the mixing chamber or manifold.

It is a further object of this invention to 35 minimize momentum effects, both in the fuel and in the air, whereby the supply of combustible mixture furnished by a carburetor embodying this invention, may accurately correspond to the requirements of the engine at any given moment.

It is a still further object of this invention 40 to provide simple and effective and easily adjusted means for regulating a carburetor embodying this invention, for the purpose of adapting it to meet the requirements of different types of engines, with which it may be 45 desired to associate the carburetor.

In the drawings:—

Figure 1 is a view representing a carburetor embodying this invention in partial vertical section, the float chamber being 50 shown largely in elevation.

Figure 2 represents a horizontal section taken on line 2—2 of Figure 1.

Figure 3 is an elevation of that portion of 55 the carburetor which includes the mixing chamber, showing that face of the mixing

chamber which is adapted for attachment to the float chamber unit.

Figure 4 is an elevation of the float chamber unit showing that face of said unit which is attached to the face of the mixing chamber unit shown in Figure 3. 60

Figure 5 is a detail view of the metering plate adapted to be interposed between the adjacent faces of the units shown in Figures 3 and 4, when the carburetor is assembled. 65

Figure 6 is a detail view similar to Figure 4 showing in a vertical section taken on line 6—6 of Figure 1, the series of passages which form a part of the fuel controlling mechanism. 70

Figure 7 is a detail sectional view taken on line 7—7 of Figure 1.

Figure 8 is a detail perspective view of the special atomizing device which I associate with the throttle valve of my improved carburetor. 75

Like parts are identified by the same reference characters throughout the several views.

In describing the carburetor illustrated in the accompanying drawing, I will first 80 identify the more conspicuous elements therein, and will subsequently describe in detail the parts which make up and are associated with these elements.

The carburetor is preferably made up of 85 two units, so constructed that they may readily be bolted together or separated. A float chamber 10 of standard construction, associated with a block 11 comprises one of the units. In the block 11 is a series of fuel 90 passages which will hereinafter be described. The second unit is built around a mixing chamber 14, to which air is admitted through an air inlet passage 17, in which a throttle valve 16 is disposed. An atomizing device 95 15 is associated with the throttle valve. Fuel is admitted to the mixing chamber through a suction regulating chamber 13, the walls of which may be integral with the walls of the mixing chamber 14. Interposed 100 between the two units is an orifice plate 12, which is shown in Figure 5.

The several elements above identified will now be described in detail.

As has been indicated above, the float chamber 10 may be of any desired construction. It is shown as a standard element provided with a settling and screening chamber 20 in its base, to which the fuel supply line may be attached by a nipple 21. The float 22 may be 110

annular and may be connected operatively to the valve stem 23, in any desired manner. I am interested in the float chamber only as a well recognized means for maintaining fuel at 5 a constant level.

Exterior to the float chamber within the block 11 is a series of bores or wells 24, 25 and 26. The relation of these wells to each other is best shown in Figures 2 and 6. It will be 10 noted that well 24 is in communication through a duct 27 with the float chamber. This duct opens into the bottom or lower portion of said well. A restricted passage 28 leads from well 24 into an enlarged passage 15 29, which opens into the larger well 26. This latter well is provided near its upper end with a vent 30 by which it is maintained in communication with the atmosphere.

The several wells 24, 25 and 26 are closed 20 at their upper ends by means of plugs 31, 32 and 33 respectively. Carried by the plug 31 is a primary fuel metering device which preferably takes the form of a tube 35 which fits closely within the restricted lower portion of 25 well 24 and is provided with a small opening 35' of predetermined size, so disposed as to be slightly above the level at which fuel will be maintained in said well. Tube 35 is bodily interchangeable with similar tubes having 30 orifices of different sizes and therefore serves the function of an adjustable valve without being subject to tampering.

The aperture 35' in tube 35, being located 35 above the level of fuel in chamber 24, has a different coefficient of discharge from that which it would have if it were submerged. The central well 25 communicates with well 24 through a duct 36, which is preferably located at substantially the same level as the 40 opening 35' so that fuel issuing from opening 35' will find a direct and non-circuitous path to well 25. The well 25 is also in communication with well 24, and with well 26 through the passages comprising ducts 28 and 29. A 45 check valve 37 at the lower portion of well 25, however, controls the flow of fuel between well 25 and the communicating passages referred to.

It will be noted that well 25 is adapted to 50 draw fuel in two ways: first, through the tube 35 and the small opening 35' therein, and the duct 36; secondly, through the very restricted passage 28 or through the more open passage 29, these latter connections being controlled 55 by the check valve 37. Within certain limits the orifice 35' will be adequate to supply to well 25 the proper amount of fuel to ensure the successful operation of the carburetor. The orifice 35' is of such a size as to operate 60 efficiently throughout the range represented by the partially closed positions of the throttle valve. The check valve 37 under such circumstances operates as a loading valve and its weight prevents any liquid from being drawn 65 into well 25 through the bottom thereof.

When, however, the throttle valve is more widely opened and the orifice 35' would not of itself be sufficient to supply adequately the proper amount of fuel for the carburation of the correct quantities of air passing through 70 the carburetor, the increased depression existing in tube 35, pipe 62, chamber 13 and recess 44 will so increase the tendency for fuel to enter well 25 through the bottom thereof that ball 37 will be lifted and the fuel will 75 flow past it. Under ordinary circumstances the flow of fuel which thus occurs will be limited by the size of the passage 28 which affords communication between the float chamber and the port controlled by valve 37. 80 Where, however, there is a sudden load on the carburetor as hereinafter explained the necessary quantity of fuel is available in well 26. In the event that such load is placed on the carburetor and the fuel in well 26 becomes 85 partially exhausted the supply in such well cannot be replenished from well 25 because of the presence of the check valve, and well 26 will consequently be filled only when a surplus quantity of fuel can flow thereto through 90 passage 28.

It will be noted by reference to Figure 4 that the block 11 is provided at its sides with ears 40, which are provided with openings 41 through which bolts may be received to secure 95 together the two units in which this carburetor is preferably constructed. That face of block 11 which appears in Figure 4 is preferably a plane face, in order that it may fit the corresponding face 42 of the casting which forms the wall of the suction regulating chamber 13. It will be noted that this casting is likewise provided with ears 43, which register with ears 40 carried by the float chamber unit. 100

In the face of block 11 there is formed a vertically disposed groove or recess 44, which is in communication through an opening 45 with the fuel well 25, the opening 45 being so disposed as to be below the level of fuel in 110 said well. When the two units of the carburetor are assembled, an orifice plate 12 is introduced between their adjacent faces and is there bound by the clamping pressure of bolts 47, which are inserted in the registering 115 openings in the ears 40 and 43. The orifice plate comprises simply a sheet of thin metal provided at its upper margin with a flange 46, which is adapted to engage the upper horizontal surface of block 11. The plate is 120 pierced by a plurality of openings which are preferably three in number, and are here designated by the numerals 48, 49 and 50. These openings are disposed along the vertical median line of the plate and afford communication, when the plate is in position, between the groove or recess 44 in the first unit and the circular suction regulating chamber 13 of the second unit. The plate thus forms, in effect, a partition in a duct composed of open- 125

ings 45, recess 44, chamber 13, and port 51, and the liquid has access from one side of this partition to the other through one or more of the apertures 48, 49 and 50, depending on the 5 height of the liquid behind the plate. Attention is called to the fact that these openings are graduated in size. The opening 48 which is located immediately above the fuel level in the first unit of this carburetor, as indicated by the dotted line in Figures 5 and 6 10 is the smallest of the three openings. Opening 50 which is farthest above the level of the fuel is the largest opening. The arrangement is such, that the amount of fuel which 15 will pass through the plate 12 may be regulated by the size and position of the openings 48, 49 and 50 to correspond accurately to the requirements of various types of engines. For example, an engine may require an 20 normal quantity of fuel to enable it to idle properly. To meet the needs of such an engine the opening 48 will be made comparatively larger than it would have to be if the carburetor were to be used with an engine of 25 more normal characteristics in this particular. The amount of vacuum in the suction regulating chamber 13 is caused by means which will hereafter be described, to vary directly in proportion to engine speeds. Consequently 30 there will be in this chamber, when the motor is idle, a very slight depression which may be barely sufficient to raise the fuel level in recess 44 to the height of the first and smallest opening 48 in plate 12. Thus 35 for the engine chosen as an example, which requires excessive fuel for idling, the hole 48 must be made comparatively large to permit sufficient fuel to pass therethrough to meet the engine requirements. The manner in 40 which the sizes of openings 48, 49 and 50 in plate 12 may be predetermined to satisfy engine requirements under various conditions will readily be seen. It may even be advisable under some circumstances so to change the 45 arrangement of these openings that opening 48 will be the largest, opening 49 the smallest, and opening 50 the intermediate size, or to adopt any other satisfactory arrangement.

50 Omitting for the time being, a description of the means whereby the depression within the chamber 13 is regulated, it need only be stated at this point that the fuel admitted to said chamber through the openings 48, 49 and 55 50 in plate 12, is allowed to flow therefrom through the port 51 adjacent the lowest portion of the chamber. This port is preferably 60 downwardly inclined and drains into an annular well at the lower end of the mixing chamber 14. It will be noted that all condensation upon the walls of the mixing chamber or of the manifold will flow downwardly along such walls and will eventually reach the well 52 which is fed by port 51.

65 The well 52 is concentric to the air inlet to the mixing chamber. The air supplied to the carburetor enters through the tubular air inlet passage 17, where it encounters the throttle valve 16. This valve comprises a disk 70 75 which is rotatable upon a shaft 53. The disk is preferably equal in diameter to the inlet passage 17 and closely fitted thereto so that when the throttle valve is disposed transversely of said passage very little, if any air will pass said disk. When the valve is opened 80 to any degree short of its wide open position, it will be encountered by the air which will be directed thereby toward two diametrically opposed sides of the passage. When the valve is wide open the air stream will be divided 85 into two equal parts thereby. As the valve is moved toward its closed position an increasingly large proportion of the air will pass the higher side of the valve and will be directed thereby against that slot 58 which is closest 90 to the fuel inlet port 51.

Set into said passage in such a manner as to be flush with the walls thereof, is a special atomizing device 15, which is shown in perspective in Figure 8. This device extends upwardly into the mixing chamber 14, in the manner indicated in Figure 1, and forms the inner wall of the annular well 52. The atomizing device is simply a tubular shell 95 with the portions 55 and 56 of its walls extended axially, upwardly, and turned inwardly at their tops to form the atomizing flanges 57, which serve as internal baffles in the air and mixture passage and appear clearly in Figures 1 and 8 of the drawings. Directly beneath each flange 57 is an extremely narrow slot or fuel orifice 58, which intersects the shell of member 15 at an angle to its axis, thereby forming arcuate cuts as shown. When the member 15 is in place, as 100 shown in Figure 1, the lowest portion of the slots 58 extends practically to the bottom of the well 52. It will be obvious that if the valve 16 starts to open, the first air admitted thereby will pass that portion of the valve 105 which is farthest from the axis shaft 53, and will thus be directed past the lowest portion of slots 58 to take up such fuel as is being delivered through said slots. If the valve is opened farther, an additional amount of fuel 110 will be supplied to the well 52 and will fill said well to an increased depth, thereby enabling the fuel to flow through the higher portions of slots 58. The additional air admitted to the mixing chamber through the valve thus 115 opened, will likewise be further distributed about the periphery of the valve and the arrangement is such, that the air admitted will correspond accurately to the fuel which flows through slots 58. The fuel delivered through 120 slots 58 into the path of the air entering the mixing chamber will be carried upwardly into the mixing chamber by the velocity of the air, but will not at first be completely 125 atomized. It is the function of the flanges 130

57 to engage the air and fuel and to serve as baffle plates to complete the atomization and create eddies which will tend to mix thoroughly the atomized fuel and air. It will be
5 noted that the flanges 57 are peculiarly fitted for their function, and are adapted to co-operate effectively with the throttle valve 16, and the fuel delivery slots 58. Attention is again directed to the fact that all fuel which
10 condenses upon the walls of the mixing chamber or manifold will be restored to the well 52, where it will join such fuel, as is being delivered through port 51 and will be reatomized by the same atomizing device
15 which handles the newly supplied fuel. It will be observed that the baffles 57 are in the same vertical or axial planes of the tube with the fuel orifices 58, and thus act effectively upon the atomized fuel and air. Furthermore,
20 more, it should be noted that the tube is cut away intermediate the baffles to provide in axial planes intermediate the fuel orifices and baffles, lateral openings. These lateral openings serve to permit reintroduction into the
25 tube of any mixture which may be drawn downwardly by the depressed area immediately above the valve at its center.

When the throttle valve 16 is entirely closed, the engine with which this carburetor
30 is used will be idling very slowly, since the valve will be disposed transversely of the inlet passage 17 instead of at an angle thereto, such air as leaks past the valve will not be directed by the valve toward either of the slots 58,
35 thus, although the air enters at high velocity it will not be effective to atomize the fuel which passes through said slots, this fuel will run down the walls of passage 17 and will collect upon the upper surface of the
40 valve 16. I have found that it may be successfully atomized by providing a very small opening 60 in the disk 16' and a tube 61 upon the upper face of the disk with one end slightly elevated and positioned directly
45 above one edge of the opening 60 and the other end opening close to the face of the disk so that the air rushing in through opening 60 will traverse the open end of tube 61 and will draw into the lower end of said tube, the fuel
50 which has collected upon the surface of disk 16'. Obviously this jet of air will effect the atomizing of fuel upon the disk.

The means by which the depression is regulated in chamber 13 includes a tube 62, which
55 enters said chamber upon one side of its outlet port 51. The tube 62 extends downwardly to a shelf member 63 and thence transversely into the inlet passage 17, where it is provided with a specially constructed portion 64.
60 The portion 64 of this tube has its upper surface cut away, as indicated in Figure 1. The stream of air entering the inlet passage 17 will be separated by the bottom of the projecting member 64 (which will have an aspirating
65 function similar to that of a Pitot tube). The

area of tube 62 is very large as compared with the area of port 51, and it will therefore be obvious that through the provision of this tube the degree of pressure or vacuum in the suction regulating chamber 13 will bear a pre-
70 determined proportionate relation to air velocities past tube portion 64 as modified by the degree of vacuum existing in the inlet passage 17, exterior to the throttle valve and by the relatively small amount of fuel, or fuel
75 and air, passing through port 51. Due to the small size of port 51 there will be very little air which will actually pass through this tube 62. Such air as does pass through this tube
80 can escape from the pressure regulating chamber 13 into the mixing chamber 14, only by passing with the fuel through the port 51. Obviously at all normal engine speeds, this port will be sealed by the fuel in the bottom of the chamber 13.

At very low engine speeds, when throttle 16 is closed or practically closed, the difference in pressures between chambers 13 and 14 will be great and any matter withdrawn from chamber 13 through port 51 will readily be
90 replaced by air admitted through tube 62. Tests indicate, however, that if the disclosure herein is followed there will be sufficient vacuum in chamber 13 to draw thereto the fuel required for the adequate and proper carburetion of all air admitted to the mixing chamber.

Having described in detail the various elements, which constitute the devices illustrated in the drawings, I will now explain the mode of operation of the carburetor.

The carburetor is attached to an internal combustion engine in the usual manner, the apertured flange 65 at the upper end of the mixing chamber being adapted to facilitate the attachment of the carburetor to an intake manifold of ordinary construction. A fuel supply line is connected to the threaded tube 21 for the purpose of supplying fuel in the usual manner to the float chamber 10. It will be understood that when the engine is cranked a certain degree of depression will be produced in the mixing chamber 14. Unlike the ordinary carburetor, the device disclosed herein is not provided with a throttle valve between the intake manifold and the mixing chamber. In a carburetor constructed in accordance with the present invention, the mixing chamber is in full communication at all times with the manifold, and is consequently subject at all times to whatever depression exists in said manifold. This fact is important for a number of reasons, one of which is that all atomization and vaporization of the fuel in the mixing chamber takes place in a
110 comparatively high degree of vacuum, and as is well known, the vaporization of any liquid is facilitated if it takes place at sub-atmospheric pressures. Furthermore, the particular position of the throttle valve makes pos-
115
120
125
130

sible its advantageous co-operation with the atomizing device 15, by which all of the fuel passing through this carburetor is atomized. The mount of fuel admitted to the mixing chamber is accurately proportioned by other means in a manner hereinafter to be disclosed, and it is therefore possible to use the single atomizing device illustrated.

It will be clear that due to the position of the throttle valve 16 in the inlet passage 17 adjacent the entrance to the mixing chamber, the operation of this valve will directly affect the depression existing in the mixing chamber and in the inlet passage. For example, if the valve is entirely closed while the internal combustion engine is in operation, the engine will be caused to idle and the depression in the mixing chamber will be high, whereas there will be a very slight degree of depression in the entrance passage 17. When the throttle valve is open to admit air to the mixing chamber, the depression therein will be lessened, but a slightly greater degree of depression will exist in the entrance passage 17, which is thus afforded more complete communication with the mixing chamber and the inlet manifold. At the same time the increased air speed past tube portion 64 will increase the depression at the mouth thereof. It will be clear that when the engine is idling and little air is entering the mixing chamber, the vaporization of the fuel in the mixing chamber will be facilitated by the comparatively high degree of depression therein. On the other hand, when the engine is operating with a wide open throttle there will be a very great rush of air past the atomizing device 15, and the highly efficient operation of this device under such circumstances will obviate the necessity for vaporizing the fuel to produce a suitable combustible mixture.

The operation of the atomizing device 15, and the auxiliary device mounted upon the throttle valve itself, has already been described, incidental to the description of the mechanical details of these parts. It will be remembered that such fuel as finds its way into the annular well 52, is delivered through the peculiar slotted ports 58 into the path of streams of air, which in entering the mixing chamber, are directed across the ports 58 by the partially opened throttle valve 16. The fuel picked up by these currents of air is carried upwardly and strikes the vaporizing flanges 57, which promote the thorough atomization and mixture of the fuel with the air when the throttle valve is entirely closed. The high degree of depression existing in the mixing chamber 14 will draw air with great velocity through the small opening 60 in the disk 16', which comprises the valve. This air will pass the mouth of the small tube 61 with an aspirating effect, thereby drawing through this tube such fuel as may have col-

lected upon the upper face of the disk 16', and atomizing it for use in the engine.

Passing now to the means which control the rapidity with which fuel is supplied to the mixing chamber, I will first take up the operation of the depression regulating device, which includes the tube 62 with its laterally projecting extension 64, and the suction regulating chamber 13 which is placed in communication by tube 62 with the inlet passage 17, exterior to the throttle valve 16. As has previously been noted, the small port 51 will not ordinarily be operative to communicate to chamber 13, the degree of depression existing in the mixing chamber 14, for the reason that fuel collecting in the bottom of chamber 13 and passing through said port will under ordinary circumstances seal the port and prevent the passage of air therethrough. While the flow of fuel through this port will be greatly accelerated by the difference in pressure, which will exist between chambers 13 and 14, such flow cannot be so rapid as to affect materially the degree of depression in chamber 13, since any tendency for the depression in chamber 13 to be increased above that which exists in the inlet passage 17, will be speedily relieved by the admission of air to chamber 13 through the tube 62.

From the foregoing, it must be obvious that the depression in chamber 13 bears a substantially constant ratio to the air flow by reason of the action of the air on the tube portion 64 and also by reason of the fact that the throttle valve, by which the rate of air flow is controlled, also affects the degree of depression existing in the inlet passage 17 which is wholly dependent upon the extent to which the throttle valve 16 has been opened. Thus, since the opening of the throttle valve also controls the amount of air admitted to the mixing chamber 14, it follows that the depression in chamber 13 is proportioned in a pre-determined manner to the amount of air admitted to the mixing chamber. It is also true in a general way, that the depression in chamber 13 bears a substantially fixed relation to the amount of fuel which will be caused to flow into said chamber, but it will be understood that this ratio is not absolutely constant, by reason of the orifice plate and check valve carried by the first unit of this carburetor, which modifies the flow of fuel to meet the abnormal requirements of the engine.

The three wells 24, 25 and 26, and the various passages associated therewith have previously been described. It will be remembered that fuel is admitted to these wells from the float chamber through an opening 27, which communicates directly with well 24, and from which the passages 28 and 29 lead to wells 25 and 26. The level of fuel in the float chamber being maintained at the height of the

dotted line in Figures 1, 5 and 6, it will be clear that the wells 24, 25 and 26 will normally be full of fuel at a corresponding level. As to well 24, the portion thereof defined by tube 35, is obviously the operative portion. As soon, however, as depression exists in chamber 13, it will be communicated from said chamber to the central well 25 through the opening in plate 12, and through the recess 10 44 and port 45. Assuming that the depression in chamber 13 increases slowly through the gradual opening of the throttle valve 16, the ball 37 at the bottom of the chamber 25 will not be lifted and the fuel flow will come 15 entirely through the small opening 35', and the passage 36. The fuel level in recess 44 will accordingly be raised by fuel entering through passage 36 to an extent determined by the depression therein, and the fuel will 20 start to flow through the lowest opening 48 in the plate 12 to the chamber 13. The size of the opening 48 is so adjusted that this opening will deliver a suitable amount of fuel to chamber 13 responsive to depression in said chamber, which is barely sufficient to raise the 25 height of fuel behind plate 12 to cover opening 48. The amount of fuel so delivered will, of course, be accurately proportioned to the amount of air passing through the inlet passage 17, so that with such air the fuel drawn 30 through opening 48 and delivered to the mixing chamber will form a suitable combustible mixture. When the depression is increased in the chamber 13, as it will be when more air 35 is admitted to the mixing chamber 14 the level of fuel behind plate 12 will be raised sufficiently to cause the fuel to flow through the opening 49, thereby adjusting the supply of fuel to the air flow and the requirements of the 40 engine. Likewise, when the throttle valve is more widely opened, port 50 will become active in delivering fuel to the regulating chamber 13. It must be clear in view of this explanation, that by changing the relative sizes 45 and positions of the ports 48, 49 and 50, in plate 12, it is possible to vary to any desired extent the proportionate amount of fuel which will be delivered to the mixing chamber responsive to any given throttle valve 50 opening.

Assume now that the throttle valve instead of being opened gradually, is opened suddenly to admit a great quantity of air to the mixing chamber 14. In the ordinary carburetor, 55 the sudden opening of a throttle valve in this manner will result in the admission to the motor of large quantities of air unmixed with fuel, whereby the motor will be caused to "miss", and "cough". In the present device, 60 however, the sudden opening of the throttle valve will result in the immediate communication to chamber 13 of an increased depression, thereby tending to raise the level of fuel in the recess 44, behind plate 12. The opening 65 35' and the passage 36 will prove insufficient

to provide the requisite amount of fuel immediately, and in consequence of the incapacity of the opening 36, fuel will be supplied to well 25 through the check valve 37. The fuel so supplied will be admitted directly from the floating chamber to some extent, through the small passage 28, but most of it will come from the well 26, which constitutes a reservoir open to atmospheric pressure through the vent 30, and the fuel which is 70 consequently available at all times to meet the sudden and increased demand, which will result when a load is suddenly placed upon the carburetor by a quick operation of the throttle valve. In this manner, I have provided 75 an immediately available supply of reserve fuel which can instantly be delivered to the mixing chamber when the throttle valve is suddenly opened.

In the ordinary carburetor, when the throttle valve is suddenly closed, there is a tendency for the engine to become choked, due to the inertia of the fuel, whereby it tends to continue to flow in comparatively great quantities to the mixing chamber. I have found 85 that such inertia effects are substantially nullified in the use of this improved carburetor, by reason of the provision of plate 12 and the three wells 24, 25 and 26, each of which has a large air space at its upper end. 90 The orifice plate 12 is extremely thin and opens into a large chamber. Thus the fuel passing through this plate does not acquire momentum to the same extent as it would in passing through a jet or tube, as it does in 95 the carburetor of ordinary construction. Furthermore, even tho the fuel should enter at three wells 24, 25, and 26 with considerable momentum (as when the throttle is suddenly opened) the presence of the air chambers at 100 the top of each well tends to absorb the momentum of the fuel and air of the momentary accumulation of the fuel in said wells, until the momentary tendency of the carburetor to produce an over rich mixture has been dissipated by the continued operation of the engine. 105

One portion of the structure of this carburetor has not yet been described, for the reason that its function can most readily be 115 made clear in connection with this discussion of the operation of the carburetor. The tube 62 is preferably provided with a valve in the manner shown in detail in Figure 7. This valve may comprise a plate 66 cut away at 67, and normally maintained by spring 68 in such a position that the aperture 67 registers with the opening through tube 62. The plate 66, however, is provided with extended arms 69, by means of which the plate may be actuated to close wholly the tube 62. When the tube is so closed and communication between chamber 13 and the inlet passage 17 is wholly cut off, it will be clear that the depression 120 in chamber 13 will immediately be tre- 125

mendously built up, due to the continual flow of fuel from chamber 13 through port 51 in response to the vacuum within the mixing chamber. Obviously the great increase of depression in the regulating chamber 13 will result in an immediately increased flow of fuel into said chamber, and thence to the mixing chamber. Thus the valve, which here is shown in the form of the plate 66, serves the purpose of a choke valve, such as is found in the ordinary carburetor, but it is particularly to be noticed that in the carburetor of my invention that the choking process is not performed by closing the air inlet to the mixing chamber. The supply of fuel delivered to the mixing chamber can be greatly increased at any time, independently of the amount of air admitted to said chamber.

From the foregoing description of the several elements which make up the carburetor of my invention together with their function and operation, it will be clear that the device shown and described herein is designed to operate in a way to satisfy all the objects herein mentioned.

I claim:—

1. In a carburetor, the combination with a mixing chamber and an air passage of reduced diameter in communication therewith, of an atomizing device having an arcuately curved wall comprising an extension of said passage into said chamber and provided with a slot starting at approximately the level of the lower portion of said chamber and having a portion extended laterally and vertically, together with means for delivering fuel to the lower portion of said chamber, whereby fuel at different levels in the lower portion of said chamber will flow through laterally offset portions of said slot into different portions of the air stream entering said chamber through said passage and said device.

2. In a carburetor, the combination with a mixing chamber, an air inlet passage thereto, and a constant-level source of fuel supply; of a regulating chamber having a plurality of ports at predetermined levels above the level of fuel at said source and in communication through said ports with said source; a duct leading from said regulating chamber to said mixing chamber and disposed for gravity delivery of fuel toward said mixing chamber from said regulating chamber; a valve controlling air flow through said inlet passage and a conduit affording communication between said passage exterior to said valve and a portion of said regulating chamber for creating in the latter a depression proportional to the depression in said passage materially higher than said duct.

3. In a carburetor, the combination with a mixing chamber and an air inlet passage leading thereto, of an atomizing device associated with said chamber, a fuel duct leading to said atomizing device and including a reg-

ulating chamber having orifices at different levels therein, said regulating chamber being arranged for gravity delivery of fuel to said mixing chamber, a constant level source of fuel supply in communication with said regulating chamber through said orifices, and means structurally independent of said duct for producing depression in said regulating chamber generally proportioned to air flow in said passage.

4. In a carburetor, the combination with a mixing chamber and an air passage of relatively reduced diameter leading vertically thereto, of a tubular atomizing device comprising an extension of said passage into said chamber and provided with slots having intermediate portions at approximately the level of the lower portion of said chamber and thence extending laterally and upwardly in both directions about said chamber, whereby fuel accumulating in said chamber externally of said device will be fed through said slots to portions of said air stream varying in circumferential extent in proportion to the depth of fuel in the lower portion of said chamber.

5. In a carburetor, a mixing chamber, an air passage of reduced diameter in communication therewith, and a tubular atomizing device comprising an extension of said passage into said chamber and provided with arcuate slots at approximately the level of the lower portion of said chamber, said device being provided with arcuate axial extensions having inwardly turned upper margins, said slots being adapted to deliver fuel to air entering through said passage and said inwardly turned margins being adapted to act as baffles to ensure the thorough mixing of said fuel with the air.

6. In a carburetor provided with a mixing chamber and an air inlet passage opening into the bottom of said chamber, an atomizing device provided with a tubular body portion adapted to fit into said air inlet passage, and to constitute a continuation of the walls of said passage into the mixing chamber, whereby a well is formed in the mixing chamber exterior to the atomizing device, a throttle valve mounted for rotation within said inlet passage upon an axis transverse thereto, whereby said valve when open will direct the air admitted therethrough against opposite sides of said tubular atomizing device, and means for directing the delivery of fuel from said well through said atomizing device to points in the path of the air admitted through said throttle valve.

7. In a carburetor provided with a mixing chamber and with an air inlet passage communicating therewith, the combination with a throttle valve disposed in said passage and movable about a pivot to direct against a wall of the passage air admitted therethrough, of a sleeve of smaller diameter than said chamber constituting an extension there-

in of said passage and slotted adjacent the lower portion of said chamber, the slot being disposed in that portion of the sleeve toward which air is directed by said valve, and said slot having its lowest portion disposed directly opposite that part of said valve having the maximum movement about said pivot.

8. In a carburetor, the combination with a mixing chamber, an air passage leading to said chamber, and a constant-level source of fuel supply; of a regulating chamber interposed between said source and said mixing chamber and provided with a series of fuel inlet ports at various levels above the normal level of fuel at said source, a first duct affording communication between said source and said ports, a second duct leading from a point of said regulating chamber lower than any of said ports to said mixing chamber, a sleeve in said mixing chamber constituting an extension of said passage and providing a well adapted to receive fuel from said second duct and from the walls of said mixing chamber, said sleeve being provided with a port for fuel delivery from said well to the path of air through said sleeve, a valve in said passage controlling air flow through said sleeve, and a tube affording communication between said passage exterior to said valve and a point in said regulating chamber above the level of said second duct.

9. In a carburetor provided with a mixing chamber, an air inlet passage leading thereto, and means for supplying fuel at a constant level, the combination of a valve controlling the passage of air through said inlet passage, an atomizing device adapted to deliver fuel into the path of said air and to effect the atomization of said fuel, a suction regulating chamber interposed between said fuel supply means and the atomizing device, a plate at the entrance to said chamber provided with apertures of predetermined sizes and location relative to the level of fuel behind said plate, and means for putting said regulating chamber into communication with the air inlet passage exterior to the throttle valve, whereby variations in pressure within said passage will be transmitted to said chamber and will affect the entrance of fuel to said chamber through the apertures aforesaid.

10. In a carburetor provided with a mixing chamber, an air inlet passage leading thereto, and a device adapted to supply fuel at a constant level, an atomizing device within said mixing chamber and adapted to form, with said mixing chamber, an annular fuel well, a pressure regulating chamber interposed between said well and said fuel supply device, and adapted to drain into said well, means for controlling the flow of air through said inlet passage, and a tube leading from said passage exterior to said air controlling means to said pressure regulating cham-

ber and terminating at a point above the bottom of said chamber.

11. A carburetor including two units, means within one of said units for supplying fuel at a constant level, a mixing chamber in the other of said units, a throttle valve controlling the admission of air to said mixing chamber, a pressure regulating chamber in communication with that portion of the carburetor exterior to the throttle valve, and a perforated plate interposed between the first and second units of the carburetor and constituting one wall of said pressure regulating chamber, the perforations of said plate being of predetermined size and position relative to the level of fuel maintained in said first unit, whereby the amount of fuel delivered from said first unit to said second unit responsive to given pressures in said pressure regulating chamber may be controlled to meet the requirements of any type of motor.

12. In a carburetor, a mixing chamber, a suction regulating chamber draining into said mixing chamber, a perforate plate forming one wall of the suction regulating chamber, means for maintaining a constant level of fuel behind said plate in predetermined relation to the perforations therein, and means for varying the pressure in said suction regulating chamber in approximately the proportion of variation in the rate of air flow to said mixing chamber.

13. In a carburetor provided with a mixing chamber and an air passage leading thereto, the combination with means for supplying fuel to the mixing chamber, of a valve in said passage and adapted to control the admission of air to the chamber, said valve being apertured, and an atomizing device mounted upon said valve in association with the aperture therein and providing an inclined duct opening immediately above said aperture at one end and substantially at the face of said valve at its other end, whereby air passing said aperture will draw through said duct fuel accumulating on the surface of said valve for the atomization thereof.

14. In a carburetor provided with a mixing chamber, fuel supply connections and means for regulating the fuel admitted to the mixing chamber through said connections to correspond to the normal requirements of a motor; the combination of a plurality of chambers introduced into said connection and provided with inter-communicating ducts, means for subjecting one of said chambers to a vacuum proportioned to the requirements of the motor, and a valve in the bottom of said chamber adapted to open in response to sudden increases of vacuum, whereby fuel stored in reserve in another of said chambers may be supplied to meet the sudden demand indicated by the suddenly increased vacuum.

15. In a carburetor, the combination of a plurality of associated units, one of said units

including a mixing chamber and an air passage leading thereto and another of said units including a source of constant-level fuel supply, a regulating chamber formed in one of 5 said units and provided with a removable plate constituting one wall thereof, a first duct adapted to drain said regulating chamber into said mixing chamber, a second duct in communication with said regulating chamber 10 extending into said passage and formed to be acted upon with an aspirating effect by air traversing said passage, a valve controlling air flow through said passage and disposed between the opening of said second duct 15 and said mixing chamber, and a third duct leading from said source to said plate exterior to said regulating chamber, said plate being provided with vertically spaced ports 20 of predetermined sizes above the normal level of fuel at said source.

16. In a carburetor, the combination with a mixing chamber having a well in its bottom and an air passage extending past said well into said chamber and provided with a throttle valve, of a regulating chamber arranged 25 for gravity delivery to said well, means for supplying fuel to said regulating chamber, a Pitot tube extending into said passage and communicating with said regulating chamber.

17. In a carburetor, the combination with a mixing chamber having a well in its bottom and an air passage extending past said well into said chamber and provided with a throttle valve, of a regulating chamber arranged 30 for gravity delivery to said well, means for supplying fuel to said regulating chamber, a Pitot tube extending into said passage and communicating with said regulating chamber for creating in the latter a depression 35 proportional to the depression in said passage, and a slide valve interposed between said Pitot tube and said regulating chamber 40 and adapted quickly to cut off communication therebetween, whereby said regulating chamber may become directly subject to depression existing in said mixing chamber and relatively increased quantities of fuel may 45 be discharged by gravity into said well.

18. In a carburetor, the combination with 50 a mixing chamber having a well in its bottom and an air passage extending past said well into said chamber and provided with a throttle valve, of a regulating chamber arranged for gravity delivery to said well, means for supplying fuel to said regulating chamber, a Pitot tube extending into said passage and 55 communicating with said regulating chamber for creating in the latter a depression proportional to the depression in said passage, said well being separated from said passage 60 by a baffle wall extending upwardly into said chamber, and a valve in said passage mounted for oscillation intermediate said baffle wall and said Pitot tube in said passage, said valve

being arranged to direct air in the direction 65 of said baffle wall.

19. In a device of the character described, the combination with a carburetor having an air passage extending substantially vertically therethrough and provided with a mixing 70 chamber comprising an enlargement of the inlet portion of said air passage, of an atomizing device applied centrally to said mixing chamber and formed to define an area through which fuel in the lower portion of said chamber must flow to reach an air stream admitted through said passage, a regulating chamber constructed at the side of said mixing chamber above said lower portion and provided with a port arranged for gravity delivery 75 from the bottom of said regulating chamber into said lower portion.

20. In a device of the character described, the combination with a carburetor having an air passage extending substantially vertically 80 therethrough and provided with a mixing chamber comprising an enlargement of the inlet portion of said air passage, of an atomizing device applied centrally to said mixing chamber and formed to define an area 85 through which fuel in the lower portion of said chamber must flow to reach an air stream admitted through said passage, a regulating chamber constructed at the side of said mixing chamber above said lower portion and provided with a port arranged for gravity delivery 90 from the bottom of said regulating chamber into said lower portion.

17. In a carburetor, the combination with a mixing chamber having a well in its bottom and an air passage extending past said well into said chamber and provided with a throttle valve, of a regulating chamber arranged 95 for gravity delivery to said well, means for supplying fuel to said regulating chamber, a Pitot tube extending into said passage and communicating with said regulating chamber for creating in the latter a depression 100 proportional to the depression in said passage and a slide valve interposed between said Pitot tube and said regulating chamber 105 and adapted quickly to cut off communication therebetween, whereby said regulating chamber may become directly subject to depression existing in said mixing chamber and relatively increased quantities of fuel may be discharged by gravity into said well.

21. A carburetor body providing a mixing chamber and a tubular inlet passage leading thereto in combination with a disk-shaped valve positioned in said passage and adapted when horizontal substantially to close said passage, said valve being provided with an aperture within its periphery affording communication between its opposite faces, together with an atomizing device comprising a short length of tubing mounted on an incline on the surface of said valve nearest to said mixing chamber and having its respective ends opening adjacent said surface and immediately above the said aperture, whereby air passing through said aperture will entrain through said short length of tubing fuel accumulating on the surface of said valve.

22. In combination a carburetor body providing a passage, an adjustable throttle valve disposed in said passage and adapted in one position of adjustment substantially to close

said passage, said throttle valve being provided with an aperture extending therethrough and affording communication at all times between portions of the passage upon 5 opposite sides thereof, together with a pipe mounted on said valve, said pipe having one end opening at the surface of said valve in a position to receive fuel accumulating thereon and the other end located immediately adjacent 10 said aperture.

23. A carburetor having a mixing chamber, an air intake passage of reduced diameter as compared to said mixing chamber leading thereto, a throttle valve mounted to oscillate 15 about a transverse axis in said passage, a tube constituting a continuation of the passage and extending into said mixing chamber in spaced relation to the walls thereof to form a liquid fuel well between the wall of 20 said chamber and the exterior surface of said tube, and means to direct the main supply of liquid fuel to said well, said tube being provided with liquid fuel orifices leading from said well through the tube wall to the interior 25 thereof, said fuel orifices being substantially opposite one another in an axial plane of said tube at substantially right angles to the axis of said throttle valve and substantially bisecting the valve, whereby air 30 flow past said valve is directed to said fuel orifices.

24. In a carburetor, a mixing chamber, an air passage of reduced diameter as compared to said chamber leading thereto, an interior 35 wall forming a continuation of said passage and leading into said mixing chamber, a throttle valve for controlling said passage pivotally mounted on an axis disposed diametrically of the passage, a liquid fuel well 40 around said wall, means for directing the main supply of fuel to said well, the wall between said valve and said chamber being formed with fuel orifices leading from said well into said passage, the orifices being disposed 45 substantially opposite one another at opposite sides of the valve axis, and in a

common axial plane of the tube which is substantially at a right angle to the valve axis, whereby air flow past said valve is directed thereby to said orifices, baffle means in said 50 passage between the valve and the mixing chamber, said wall having lateral openings in axial planes of the passage intermediate said fuel orifices.

25. In a carburetor provided with a mixing chamber and fuel supply connections, certain parts of said connections being adapted to maintain fuel at varying levels, and an interchangeable partition plate interposed in said fuel supply connections adjacent said 60 parts and provided with a series of substantially vertically disposed openings of predetermined size and position relative to the normal level of fuel standing in said connections behind said partition plate. 65

26. A carburetor comprising two units, means disposed in one of said units for supplying fuel at a constant level, means disposed in the second unit for combining said fuel with air to form a combustible mixture, 70 a fuel supply duct leading between said units, and an interchangeable partition plate secured between said units in said duct and provided with vertically spaced orifices controlling fuel delivery through said duct and 75 disposed above the normal level of fuel in said duct behind said partition plate.

27. In a carburetor having an air intake passage, a throttle valve disposed therein, said passage forming a depression chamber 80 behind said valve, means to effect the accumulation of liquid fuel on said valve within said chamber when said valve is closed, said valve being provided with a small aperture through which air is drawn into said depression chamber, an aspiratory tube mounted on said valve, and located within said chamber, and rendered operative by the air emerging from said aperture to remove and atomize the accumulated fuel. 85

ELMER J. MANNING.
